UNITED STATES PATENT OFFICE.

CLARENCE R. GRAHAM, OF SAN FRANCISCO, CALIFORNIA, ASSIGNOR TO JAMES GRAHAM MANUFACTURING CO., OF SAN FRANCISCO, CALIFORNIA, A CORPORATION OF CALIFORNIA.

GAS RANGE.

Application filed June 23, 1924. Serial No. 721,621.

To all whom it may concern:

Be it known that I, CLARENCE R. GRAHAM, a citizen of the United States, residing in the city and county of San Francisco and 5 State of California, have invented new and useful Improvements in Gas Ranges, of which the following is a specification.

This invention relates to gas ranges and particularly to such ranges of the closed top

10 type, as distinguished from those having an open or grating top plate above the gas burners. Ranges of the latter type are most common and it is obvious that in such ranges the open top permits free passage of air therethrough to the burners. Ranges of the closed type, however, must receive their supply of air from another source. As thus far devised such ranges have been constructed to receive the air to the burner chamber 15 solely through the front of the range. As thus constructed insufficient air is supplied to the burners and particularly to the rear burners for supporting complete combustion. This condition results in great inefficiency, 20 loss of heat and considerable danger due to the formation of carbon monoxide gases. The primary object of my invention is to provide an improved gas range wherein these objects are entirely eliminated.

25 More specifically it is an object of my invention to provide an improved gas range having a warming oven beneath the burner chamber and an opening in the partition between the oven and burner chamber beneath 30 each burner through which openings air is supplied directly to the burners in a manner to support complete combustion, thus securing efficient operation of the burners and eliminating formation of poisonous gases.

35 Another object of my invention is to provide a closed grid top plate for a gas range with a downwardly extending flange or baffle plate about certain of the grid openings whereby the gas burners therein are 40 protected from interference by air currents and adjacent burners.

45 With the above and other objects in view, my invention consists in the features of construction and operation set forth in the following specification and illustrated in the 50 accompanying drawing. In such drawing annexed hereto and forming a part of this specification, I have shown certain specific embodiments of my invention, but it will be 55 understood that the invention can be other-

wise embodied and that the drawing is not to be construed as limiting the scope of the invention, the claims appended to this specification being relied upon for that purpose.

Referring to the figures of the drawing: 60

Fig. 1 is a transverse sectional view through a gas range embodying my invention, this view being taken approximately on line 1—1 of Fig. 2.

Fig. 2 is a fragmentary plan view thereof. 65

Fig. 3 is an inverted perspective view of the top plate of the range.

Referring more specifically to the drawing by reference characters, 1 indicates the body portion of my improved range supported on legs 2. As illustrated this body comprises a warming oven 3, combustion chamber 4, and a top or grid plate 5. The oven may be provided with a closure door 6 at the front of the range, and the top plate is provided with a plurality of grid openings 7 therein, each adapted to receive a closure grid 8. Two of the said openings 7^a are at the front of the range and the other two 7^b are at the rear thereof. A gas burner 9 is mounted in the combustion chamber 4 beneath each grid opening 7. 70

75 When using the range with the grid openings 7 closed, either by the grids 8 or by cooking utensils seated on the top plate over the openings, the top plate is entirely closed and air must be supplied to the burners from beneath. Heretofore the opening 10 at the front of the combustion chamber has been 80 solely relied upon to supply this air. The front burners 7^a, being near the air inlet, have obtained sufficient air in this manner to operate to a fair degree of satisfaction. The supply of air or oxygen to the rear burners, however, has been so limited that 85 such burners have operated very inefficiently and with considerable danger. 90

95 It will be understood that air entering the combustion chamber 4 through the opening 10 thereof comes first to the front burners which absorb most of the oxygen therefrom. The resulting gases pass therefrom rearwardly and the rear burners must depend on these gases for their supply of oxygen. Obviously these rear burners will 100 operate at only partial combustion, thus resulting in a great heat loss and the formation of poisonous fumes known as carbon monoxide gas. It may furthermore be 105 stated that the air entering from the front 110

and passing rearwardly in the manner just described causes a draft which considerably interferes with the proper operation of the rear burners. When using both the 5 front and rear burners with the top plate 5 entirely closed the supply of oxygen to the rear burners and the interference of air currents thereover have been known to become so pronounced as to entirely extinguish the flames of such rear burners. It 10 is one object of this invention to provide a range wherein these objections are eliminated, and my improved construction, whereby such object is accomplished, will now be 15 described.

The bottom plate 11 of the combustion chamber 4 is the top plate of the warming oven 3, such plate providing a wall between these two chambers. To provide 20 each burner 9 with sufficient air for complete combustion, I form a plurality of openings 12 in this plate. Preferably, as illustrated, I provide one such opening in the plate directly beneath each burner. In 25 such construction the air enters the burner from beneath, instead of from the side as heretofore, and causes the flame to burn upwardly onto the grid without interference by laterally moving air currents. Such operation not only provides a more complete 30 combustion, but also places the flames up into the openings 7 where their heat is absorbed with the greatest efficiency. To furthermore facilitate this action, I preferably provide a flange 13 around each opening 12, such flange preferably extending upwardly toward its burner. To still further facilitate the operation of the burners, I may provide openings 14 and 15 through 40 the back wall of the range. The openings 14 enter the oven 3 and permit air to enter thereinto and the openings 15 enter the combustion chamber 4 and permit the burned gases to escape therefrom.

45 As has been heretofore stated, the movement of the burned gases rearwardly have heretofore caused the front burners to interfere with the proper operation of the rear burners. To prevent such action, I 50 provide a downwardly extending flange or baffle plate 16 about each rear opening 7^b between such opening and the adjacent front opening 7^a. These baffle plates are preferably bolted to the top plate 5 as illustrated. It will be understood that these 55 plates deflect the gases around the rear burners and prevent draft interference therewith from the front burners. This action will be clear by referring to Figs. 1 and 60 2 of the drawing.

Having thus described my invention, what I claim and desire to secure by Letters Patent is:

65 1. A gas range comprising a body portion supported by legs, a closed top plate

supported on the body and having a plurality of removable grids, a gas burner beneath and closely adjacent each grid, and a bottom plate beneath the top plate and burners providing a single combustion 70 chamber in which the burners are housed, the bottom plate having an opening therethrough beneath each burner to permit the passage of air upwardly therethrough to the burners. 75

2. A gas range comprising a body portion supported by legs, a closed top plate supported on the body and having a plurality of removable grids, a gas burner beneath and closely adjacent each grid, a bottom plate beneath the top plate and burners providing a single combustion chamber in which the burners are housed, the bottom plate having an opening therethrough beneath each burner to permit the passage of air upwardly therethrough to the burners, and an upwardly extending flange formed integral with and surrounding each of said openings beneath each burner for directing the air upwardly to the burners. 80 85

3. A gas range comprising a body portion supported by legs, a closed top plate supported on the body and having a plurality of removable grids, a bottom plate beneath the top plate and burners providing a single combustion chamber, a gas burner in the chamber beneath each grid and closer to the grid than to said bottom plate, a chamber beneath the bottom plate, the bottom plate having an opening therethrough beneath each burner to permit the passage of air upwardly therethrough to the burners, and an upwardly extending flange connected to and surrounding each of said openings beneath each burner for directing the air upwardly to the burners. 90 95 100

4. A gas range comprising a body portion supported by legs, a warming oven and a single combustion chamber in the body portion, a closed top plate supported on the body above the combustion chamber and having a plurality of removable grids, a wall beneath the top plate providing a partition between the warming oven and the combustion chamber, and a gas burner in the combustion chamber beneath each grid, the partition wall having an opening therethrough beneath each burner to permit the passage of air upwardly therethrough to the burners. 110 115 120

5. A gas range comprising a body portion supported by legs, a warming oven in the body portion, a top plate supported on the body above the oven and having a plurality of removable grids, a gas burner beneath each grid, and a bottom plate beneath the top plate and burners providing a partition between the warming oven and the burner chamber, the bottom plate having openings therethrough for permitting the passage of 125 130

air to the burners and the back wall of the body portion having openings therethrough into the warming oven and burner chamber to respectively permit the passage of air into the oven and out of the burner chamber.

6. A gas range comprising a body portion having a single housed combustion chamber therein, a top plate supported on a body over the chamber and having a plurality of 10 grid openings therein, each superimposed over a gas burner, and curved flanges connected to the plate respectively adjacent the edges of certain of the openings and extending downwardly therefrom and partially surrounding the openings to protect the burner from interfering air currents.

7. A gas range comprising a body portion having a single housed combustion chamber therein, a top plate supported on a body 20 over the chamber and having a plurality of grid openings therein, each superimposed

over a gas burner, and curved flanges connected to the plate respectively adjacent the edges of certain of the openings and extending downwardly therefrom and partially surrounding the openings between such openings and the adjacent openings to protect each of such burners from interference by an adjacent burner.

8. A gas range comprising a body portion having a single housed combustion chamber therein, a top plate supported on the body portion of the chamber and having front and rear openings therein each superimposed over a gas burner, and a curved flange 35 connected to the plate adjacent the edge of the rear opening and extending downwardly therefrom and partially surrounding the rear opening between such opening and the front opening to protect the rear burner 40 from interference by the front burner.

CLARENCE R. GRAHAM.
